UNITED STATES PATENT OFFICE.

FRANZ HARDTMUTH, OF BUDWEIS, AUSTRIA-HUNGARY.

PENCIL OR CRAYON HOLDER.

SPECIFICATION forming part of Letters Patent No. 276,812, dated May 1, 1883.

Application filed July 24, 1882. (No model.)

To all whom it may concern:

Be it known that I, FRANZ HARDTMUTH, a subject of the Emperor of Austria, residing at the city of Budweis, in the Empire of Austria-Hungary, and temporarily at Vienna, have invented certain new and useful Improvements in Pencil or Crayon Holders; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to certain improvements in pencil-holders; and it consists in constructive features whereby the pencil may be released from the gripping-jaws by pressure upon the handle, and again securely held against 20 displacement when said pressure upon the handle is removed, as hereinafter fully described, and specifically pointed out in the claims.

In the accompanying sheet of drawings, Figure 1 is a longitudinal section, showing the 25 parts of the pencil-holder in their normal position for use of the pencil. Fig. 2 is a sectional elevation, showing the parts of the pencil-holder in the position they assume to release the pencil from the gripping-jaws. Figs. 3, 4, 30 and 5 are sections taken on lines $x-x$, $y-y$, and $z-z$, respectively, of Fig. 1; and Fig. 6 is a face view of the guide-plate.

In the above figures of drawings like letters of reference indicate like parts.

35 A is the handle, made of any suitable material, such as wood, ivory, rubber, metal, or other preferred material. It is tubular and of uniform interior diameter throughout the greater portion of its length, said interior diameter being reduced to form the annular shoulder or abutment a' , from which point it tapers to the solid portion of the said handle, forming at that point an abutment, a^2 , and upon the lower end of the handle is screwed or otherwise securely attached a metallic sleeve, a , for purposes hereinafter described.

40 B is the pencil-tube or holder proper, terminating at its outer end in a screw-threaded shank, b , by means of which it is screwed into 45 the solid portion of the handle A, below which

shank said tube is slightly enlarged to form a bearing that abuts against or is seated upon the abutment or end wall, a^2 , of the tapering portion of the cavity of the handle. The tube B, at its lower or outer end, is slotted to form 55 a series of gripping-jaws, b' , that serve to hold the pencil C, and said tube is inclosed within a tube, D, that is provided with a longitudinal slot, b^6 , (shown in dotted lines, Fig. 2,) at its upper or inner end, and a conical head, d' , at its 60 lower or outer end, upon which latter is screwed a conical cap or sleeve, E, whose interior diameter is made to taper from its inner to its outer end at which point the aperture is large enough to allow the pencil C to slide through 65 without binding it. The upper slotted end of tube D is screw-threaded exteriorly, and upon it is fitted a sleeve, f' , screw-threaded exteriorly also, and provided at its threaded portion with a longitudinal slot, f^3 , that registers 70 with the slot in the tube. To this sleeve f' are attached a series of spring arms or levers, f , at which point said sleeve is of greater diameter than at its threaded portion, forming a shoulder, f^4 , that serves as a seat for a locking-nut, b^4 . 75 The tube B is provided with a flat locking stud or plate, b^2 , of a length equal to or nearly equal to the unthreaded portion of the sleeve f' , so that when said tube is inserted within the tube D the projecting locking stud or plate b^2 will lie 80 within the slot of said unthreaded portion and be held there against longitudinal motion by the nut b^4 , thus locking the sleeve f' , with its spring-levers f , rigidly to the pencil-tube B, and without interfering with the longitudinal motion of the tube D upon tube B, for purposes 85 presently explained.

Upon the upper end of tube D is screwed a nut, b^3 , and between the latter and the nut b^4 is mounted a coiled spring, b^5 , that exerts 90 its pressure upon said nut b^3 , and tends to draw the tube D upward toward the handle, and with it the cap or sleeve E, which latter, by reason of its tapering interior diameter, compresses the spring gripping-jaws b' upon 95 the pencil and holds the latter securely in position.

The upper or inner portions of the head d' on tube D may be of semi-spherical form, as shown at d^2 , or it may be made of a tapering 100

or conical form, so as to present an upwardly-inclined face to the end of the spring-levers f . These lever-arms have their extremities f^2 beveled to fit the inclined face of the head d' , 5 and they are guided by a plate, e , attached to the upper or inner end of the cap or sleeve E above its screw-threaded portion, which cap is slightly enlarged at that point. The plate e has a series of recesses, e' , equal in number 10 to the number of lever-arms f employed. As shown in Fig. 6, the plate is recessed for the reception of the lower or outer end of five such arms, though more or less of them may be employed, as will be readily understood, and as 15 may be conveniently employed upon a given size of holder.

As will be seen, the extent of the movement of the tube D upon tube B may be adjusted within certain limits by adjusting the nut b^3 20 toward or from the nut b^4 , and thus cause the cap E to exert more or less power upon the gripping-jaws, whereby leads or pencils of different diameters, within certain limits, may be employed with the holder, which is a great advantage. 25

The metallic sleeve a on the outer end of the handle has its outer periphery made tapering inwardly, as shown, and serves to limit the outward movement of the spring-levers f at their 30 upper end, and also relieves the guide-plate e from too great a strain.

From the detailed constructive description of the pencil-holder above given its operation may be described in a few words and readily 35 understood. It will be remembered, first, that the spring-levers f are rigidly connected to the lead-holder B , and the latter is rigidly connected to the handle A ; secondly, that the tube D is rigidly connected to the tapering cap E 40 and capable of longitudinal motion upon tube B ; thirdly, that the tube B , properly speaking, serves as a rigid bearing to one end of the spring b^5 , and the tube D as the body upon which said spring exerts its power. It is evident that when the holder is in its normal position, as shown in Fig. 1, the spring b^5 presses the tube D upward, and with it the cap E , the interior of which, being tapering outwardly, compresses the spring-jaws b' upon the lead or 45 pencil and causes them to grip the latter securely. If, however, the spring-levers are compressed, their beveled ends will exert a corresponding pressure against the tension of the spring upon the head d' of tube D and force 50 said tube and its head outward or downward, and as the cap E is rigidly connected with the latter said cap is forced outward also, which movement widens its interior passage, owing 55 to its tapering form, and causes the jaws b' to release the pencil, which is now free to slide 60 out of the holder. The moment, however, that the pressure upon the spring-levers is released the tension of the spring b^5 will again carry 65 the tube B and parts connected therewith upward and cause the gripping-jaws b' to close upon the lead or pencil.

Having now described my invention, what I claim is—

1. In a pencil-holder, a tube provided with gripping-jaws to contain and grip the pencil, a handle, and a series of levers rigidly connected with said pencil-holding tube, and appliances, substantially as described, to cause the gripping-jaws to release the pencil when pressure is applied to the spring-levers, substantially as and for the purpose specified. 75

2. In a pencil-holder, a tube provided with gripping-jaws to contain and grip the pencil, a handle, and a series of spring-levers, both rigidly connected with the pencil-holding tube, in combination with appliances, substantially as described, to cause the gripping-jaws to release the pencil when pressure is applied to the spring-levers, and again automatically grip the pencil when the pressure 85 upon the levers is removed, substantially as and for the purposes specified. 80

3. In a pencil-holder, the combination, with the pencil-holding tube B , provided with gripping-jaws b' , the spring-levers f , and handle A , rigidly connected to said tube, of an inclosing-tube capable of longitudinal motion 90 upon tube B , and carrying a tapering sleeve or cap adapted to engage the gripping-jaws of tube B , and appliances, substantially as described, whereby said tapering sleeve or cap is normally held in engagement with the gripping-jaws and released therefrom by the compression of the spring-levers, as set forth. 95

4. In a pencil-holder, the combination of the tube B , having a projecting locking-plate, b^2 , the spring-levers f , their slotted retaining-sleeve f' , and the nut b^4 , with the slotted tube D , whereby said tube B and spring-levers are rigidly connected together without interfering 100 with the longitudinal motion of the tube D upon tube B , substantially as and for the purposes specified. 105

5. The combination, in a pencil-holder, of a pencil-holding tube provided with gripping-jaws, an inclosing-tube provided with means, substantially as described, to lock said jaws upon the pencil, said inclosing-tube being capable of longitudinal motion upon the pencil-tube, a series of spring-levers rigidly connected with the pencil-holding tube, and adapted for operation to unlock or release the gripping-jaws through the medium of the inclosing-tube, and appliances whereby the longitudinal movement of the latter tube may be 115 regulated to lock the gripping-jaws with more or less force upon the pencil, or to adapt the holder for use with pencils of different diameters, as set forth. 120

6. The combination of the tube B , the 125 spring-levers f , rigidly connected therewith, the slotted tube D , carrying the cap E , the locking-nuts b^3 b^4 , and the spring b^5 , all constructed and arranged for co-operation as described. 130

7. The combination, with the tube B and its spring-levers f , of the spring-actuated tube

D, provided with a head, d' , and the sleeve or cap E, all constructed for co-operation substantially as and for the purposes specified.

8. The combination of the tube B, its 5 spring-levers f, and the handle A, provided with the sleeve a of the spring-actuated tube D, provided with the head d' , and the sleeve E, provided with the guide-plate e, all con-

structed and arranged for co-operation substantially as and for the purposes specified.

In testimony whereof I affix my signature in presence of two witnesses.

FRANZ HARDTMUTH.
